UNITED STATES PATENT OFFICE

DURBIN C. HODGKIN, OF WASHINGTON, DISTRICT OF COLUMBIA, ASSIGNOR OF ONE-FOURTH TO TOM B. OWENS, OF FORT WORTH, TEXAS

ADVERTISING DEVICE AND METHOD OF MAKING THE SAME

Application filed October 5, 1928. Serial No. 310,581.

This invention relates to an improvement in advertising devices and methods of making the same.

The object of the invention is to provide 5 novel and attractive advertisements of an unusual character for the purpose of attracting attention and fixing in the mind of the person viewing the advertisement the object thereof.

10 This object is carried out by creating variations in the advertisement, either of allusions of motions or of changes in the pictorial illustration of the signs themselves.

By the use of this invention, I make an object or the like disappear by transmitted rays 15 of white light. I may paint an object or the like in, for instance, yellow, surrounding it with, for instance, a blue ground. On the back of a translucent surface will be painted 20 a yellow ground and the object or the like will be backed up by blue. When white light rays are transmitted the entire surface will appear solid green, entirely obliterating the object or the like on the front. I do not con- 25 fine the foregoing to the colors named, but have discovered that any colors—even black and white—may be employed in the same manner, for instance, red backed up with black will make a brown surface and if the 30 surrounding ground be brown, the result is equally effective. No so-called colored light rays are necessary for this effect.

I have discovered that white inks, paints, crayons, etc. commonly known to art as 35 “opaque”, are, when applied thin and in the proper consistency, decidedly transparent or translucent and when subjected to the rays of transmitted “white light” become a strong grey or brownish grey. If then, a white 40 image be painted on a grey ground and subjected to transmitted white light rays, the grey will remain grey while the white will appear as a neutral tone of brownish grey and 45 disappear, becoming completely lost in the grey background. This is also reversible, the image may be grey and the ground white.

In the accompanying drawings:

Fig. 1 is a perspective view of the sign cas- 50 ing;

Fig. 2 is a front view of a sign embodying the present invention;

Fig. 3 is a rear view of the same, illustrating the picture painted on the back;

Fig. 4 is a front view of another sign; 55

Fig. 5 is a rear view of the same;

Figs. 6 and 7 are corresponding views of another sign illustrating another modification.

The casing illustrated in Fig. 1 is designated generally by the numeral 1, being provided with a lamp 2, arranged therein for transmitting rays of light from the rear through the sign 3. This light 2 may be flashed or alternately switched off and on in any well known manner, as by the use of thermostatic or other flasher switches. The sign 3 is carried by a frame 4 which may be removable from the casing 1 to facilitate changing of the sign. Lights may be arranged in front of the sign 3 or the front may be illuminated by day-light as found desirable. However it is to be understood that the use of the term “transmitted light” or its equivalent refers to the light transmitted from the lamp 2, from the back of the sign, while “reflected light” refers to the illumination from the front. It is also understood that the advertisement may be printed, drawn or otherwise applied to the sign 3, and while it is referred to throughout this specification as being painted thereon, this is merely for purposes of illustration. 75

In Figs. 2 and 3, by the flash of transmitted light rays the dog is made to roll his 85 eyes from one side to the other, his mouth opens, his tongue protrudes, and his ear pricks up. The numeral 5 illustrates the dog's ear flapped down, 6 shows the dog's ear pricked up. The dog's eyes are cast to the right, as at 7 in Fig. 2, but are looking straight out, as at 8 in Fig. 3. 9 in Fig. 2 shows the dog's mouth closed and 10 in Fig. 3 shows the dog's mouth open displaying his tongue, teeth, etc. 90

This change is accomplished by the use of transmitted light through any translucent or transparent surface and may use what is commonly known as “white light”, in which as near as scientifically possible all the visi- 95 100

ble rays of the spectrum are present. These rays have a tendency, for instance, in Fig. 1 to dissipate the strength of the front eyes to such an extent that, when placed in juxtaposition to the back eyes, which are enhanced in color value, the front or reflected light eyes are completely obliterated while the back eyes are thoroughly and intensely visible, causing such an illusion that the dog's eyes apparently roll from side to side when the transmitted light rays are flashed off and on alternately.

In Fig. 2, the dog's ear is shown down and may be of a slightly lighter or slightly darker hue or shade or color than the dog's head. In the former case, in Fig. 3, the ear 5 would be darkened on the back of the picture to match the color of the head in Fig. 2, causing its total disappearance under transmitted rays. In the latter instance, where the ear is painted, darker than the head on the front, then the head on the back would be darkened sufficiently to cause the total disappearance of the ear under transmitted rays. Employing, also in this instance, the method of painting an object on the back of a translucent surface which is invisible under reflected rays, because of the opacity of the surface under reflected rays, and visible under transmitted rays, I paint an extra dog's ear 6 straight upon the back so that when the transmitted rays flash on they absorb the front or down ear, rendering it invisible and cause the up ear 6 to become visible. By alternately flashing the transmitted rays off and on the action of a flapping ear becomes startlingly natural.

The outline of the dog's mouth is shown at 9. On the reverse or back picture at 10 I paint the dog's mouth open and by using a darker shade into which the mouth line 9 is absorbed or lost, by transmitted rays, the illusion of the dog opening and closing his mouth is created perfectly by alternately flashing the transmitted rays off and on.

I do not confine myself to the foregoing motions of the dog. He may wag his tail, raise his foot, jump through a hoop or any other action common to animals.

In Figs. 4 and 5, I show the new method of causing grey objects to disappear on white by transmitted rays. In Fig. 4 the coat, cape, etc. 11 is painted in pure white. The lines at 12 are painted in grey, when the transmitted rays penetrate the translucent or transparent material, this white surface (coat) will turn exactly the same grey as the lines 12, rendering them totally invisible.

In Fig. 5, the back or reverse picture, I paint the body 13 in any color, or black or white, and make use of the method of painting an object on the back by painting the arms 14 and the outstretched cape 15 in any color or shade, including black, and when the transmitted rays flash on, absorbing the

grey lines 12, rendering the outline of the body perfectly smooth and the outstretched arms and cape, etc., are made visible, and the startling illusion of the woman opening her coat and displaying corset, bodice, nude, etc., is created.

By this same method, using a grey background around the woman with white legs and by outlining one leg on the reverse picture, and painting an extra leg straight up on the rear, she can be made to kick perfectly. Any other human action can be so portrayed. This absorption is reversible. The background may be either grey or white, and the object the reverse.

In Fig. 6, I show a winter scene, snow, ice, bare trees, etc. In Fig. 7, the reverse or back picture, I show a summer scene. By the alternate flashing of the transmitted lights, these scenes are made to quickly change from one to another. In this picture I make use of the method of absorbing by transmitted white light rays any light shade or color or any dark shade or color alike or different, both being printed on the front side of the surface to be displayed.

For instance, in Fig. 6 the trunk of the tree 26 may be dark brown with yellow or blue white highlights to indicate snow. When viewed by the transmitted light these snow spots will be absorbed and totally disappear in the dark brown of the tree trunk yet both are painted on the front of the surface. The dark ever-green trees 27 in Fig. 6 may have yellow, thin white or light green high lights yet when viewed by transmitted light these will disappear and absorb into the dark green of the trees.

Also in this picture I make use of the method of absorbing a color or shade, with transmitted rays, by painting on the back or reverse side an entirely different color. For instance, the ground 28 may be painted in thin white with appropriate shadows to indicate drifts of snow and the water 29 may be painted in dull white-grey to indicate ice. On the reverse side in Fig. 7, the ground 30 will be painted in vivid greens and yellows to indicate grass, while the water 31 will be painted in vivid blue (this also applies to the sky) and the mountains will be painted in purple. Leaves will be painted for the trees, etc. Under the transmitted rays the thin white and shadows of 28 will totally disappear and become brilliant greens, etc. of 30. The dull white-grey of 29 will become vivid blue; the sky will change to blue and the mountains from white to purple. Leaves will appear on the trees and the entire scene change from winter to summer in a startling manner.

I do not confine myself to the above change of scenery. By the use of the above methods a bright day-light scene may be completely changed to a night scene in which the sky

turns dark and the moon and stars appear, or a scene of a ship on an ocean may change to an automobile on a road or any other complete change may be effected. I do not confine myself to any particular colors in this effect using such as may be desired for artistic and life-like pictures.

I claim:—

1. The method of making advertising matter including illustrating at least a portion of an object on a side of a display surface to be viewed by reflected light, said portion being illustrated by grey and the body portion thereof by white, to disappear when viewed by transmitted light.

2. The method of making advertising matter including illustrating an object on a side of a display surface to be viewed by reflected light, said object being indicated by grey and the body portion thereof being white, to disappear when viewed by transmitted light, and illustrating the same object behind the display surface to be viewed by transmitted light, said second illustration having at least portions thereof corresponding to portions of the first illustration in different positions therefrom, to indicate a change of position or motion.

3. The method of making advertising matter comprising illustrating at least a portion of an object in a neutral color on a side of a display surface to be viewed by reflected light, surrounding the same with a color to which said first mentioned color is neutral, and subjecting said illustration to transmitted light to cause a disappearance thereof.

4. The method of making advertising matter comprising illustrating an object on the front side of a display surface to be viewed by reflected light, said object having the outline thereof in a neutral color, surrounding the same with a color to which said first mentioned color is neutral and subjecting said object to transmitted light to cause a disappearance thereof.

5. The method of making advertising matter including illustrating an object in white and a neutral color on a display surface to be viewed by reflected light, which when subjected to transmitted light will merge, disappear and absorb the outline of said object.

6. The method of making advertising matter including illustrating an object in white and a neutral color on a display surface to be viewed by reflected light, which when subjected to transmitted light will merge, disappear and absorb the outline of said object, and illustrating an object behind said display surface to be viewed by transmitted light.

7. An advertising device comprising translucent material having a display applied to a surface thereof and represented by neutral and white colors, to be viewed by reflected light, said neutral colors merging with the

white and disappearing when subjected to transmitted light.

8. An advertising device comprising translucent material having a display applied to a surface thereof and represented by white and neutral colors, as brownish grey or the like to be viewed by reflected light, said display being adapted to be subjected to transmitted light to cause the neutral colors to merge with the white and cause a disappearance of the object.

9. An advertising device comprising a translucent surface having a display applied thereto, and represented by neutral and white colors to be viewed by reflected light, said white surrounding the neutral color or colors to cause a mergence therewith and a disappearance when subjected to transmitted light.

10. A method of making display matter comprising illustrating a scene in white and a color neutral thereto on a display surface to be viewed by reflected light, said colors being disposed in relation to each other to cause the scene to disappear when subjected to transmitted light, and illustrating a different scene behind said first-mentioned scene to be viewed when subjected to transmitted light.

11. A method of making display matter comprising illustrating a scene in white and a color neutral thereto on a display surface to be viewed by reflected light, said colors being disposed in relation to each other to cause the scene to disappear when subjected to transmitted light.

In testimony whereof I affix my signature.
DURBIN C. HODGKIN.
